UNITED STATES PATENT OFFICE

101,742

DESIGN FOR A WHEEL OR SIMILAR ARTICLE

George Albert Lyon, Detroit, Mich.

Application March 13, 1936, Serial No. 61,617

Term of patent 14 years

To all whom it may concern:

Be it known that I, George Albert Lyon, a citizen of the United States, and a resident of the city of Detroit, in the county of Wayne and State of Michigan, have invented a new, original, and ornamental Design for a Wheel or Similar Article, of which the following is the specification, reference being had to the accompanying drawing forming a part thereof.

On the drawing:

Figure 1 is an outer side view of a wheel, showing the wheel with a central disk through apertured portions of which rear portions of the wheel project.

Figure 2 is a fragmentary cross-sectional view taken on the line II—II of Figure 1, showing clearly the contour of the disk.

Figure 3 is an enlarged fragmentary sectional view taken on the line III—III of Figure 1, showing one of the portions of the wheel projecting through an aperture in the disk.

I claim:

The ornamental design for a wheel or similar article as shown and described.

GEORGE ALBERT LYON.
